PRINTING PLATE AND TAB.

1,161,045.

Specification of Letters Patent. Patented Nov. 23, 1915.

Application filed November 8, 1914. Serial No. 870,130.

To all whom it may concern:

Be it known that I, ROBERT G. GRISWOLD, citizen of the United States, residing at Chattanooga, Tennessee, have invented certain new and useful Improvements in Printing Plates and Tabs, of which the following is a specification.

My invention is an improvement upon record plates and tabs used in address printing apparatus in which a series or list of plates are fed to an impression point to make impressions from the characters, on or carried by said plate, upon any suitable articles or form sheets, it being understood that the plates may be used for printing not only addresses but matter designed for other purposes if desired.

A printing plate of this general character is disclosed in Letters Patent of the United States granted to D. P. Montague and U. G. Lee, #1110221, September 8, 1914.

My invention consists in the features and combination and arrangement of parts hereinafter described and particularly pointed out in the appended claims.

In the accompanying drawings Figure 1 is a plan view of a record or printing plate with my improvements in one form combined therewith, this view being of the printing face of the plate; Fig. 1^a is a sectional view of the tab and plate of Fig. 1; Fig. 1^b is an edge view of the tab of Fig. 1; Fig. 2 is a back view of a plate substantially like that of Fig. 1; Fig. 3 is a front view of a printing plate combined with tabs of different forms from those shown in Fig. 1; Fig. 3^a is a sectional view of the plate of Fig. 3 on line 3^a—3^a thereof; Fig. 3^b shows one of the tabs in edge view and in face view; Fig. 3^c is a view of a portion of the edge of the plate of Fig. 3; Fig. 4 is a face view with other forms of tabs; Fig. 4^a is a detail view of one of the tabs of Fig. 4; Fig. 5 is a view of a part of a plate with still other forms of tabs; Figs. 5^a and 5^b show different views of tabs.

The invention is shown in the above drawings as incorporated with a printing plate of the Montague type, though it will be understood that as to some of its aspects it might be used with plates of a different make, and I do not limit myself in this respect except as specifically pointed out in the appended claims.

The printing plate shown has a raised central portion 1 carrying the printing characters (not shown) which are embossed thereon, and its margins 2 are depressed and rolled or turned upwardly upon themselves, leaving a recess therein. These rolled margins are located along the longitudinal edges of the plates.

At 3, Figs. 1 and 2, is shown a tab to bear any desired information of an index or indicating character. For holding this tab in place the rolled margin of the plate is cut away or omitted at one point intermediate of its length, for instance between the points *a* and *b*, Figs. 1 and 2, and in the space thus provided the tab 3 is located, it having end portions 4, 5, extending in opposite directions and into the recesses in the adjacent portions of the rolled margin of the plate, the terminal openings at *a* and *b* of the said rolled marginal portions being adapted to receive the end portions of the tab. These end portions extend from these terminal openings a sufficient distance longitudinally within the recess of the rolled margin to securely hold the tab in place and to permit it to be shifted to different positions in a direction lengthwise of the plate or rolled margin.

The body of the tab may be of various forms and dimensions, but in the particular form shown the main part is wider than the extensions or end portions 4 and 5 so that index marks or other inscriptions carried by or formed on the tab may be of proper size for quick reading or of proper size to carry considerable matter.

The tab is movable from one position to another. In Figs. 1 and 2 it is shown as occupying a position near the adjacent end of the printing plate, but it may be shifted to occupy a position nearer the center of the printing plate by simply applying pressure of the finger thereto. In one location it serves because of its position relative to the plate and without regard to any marking that may be thereon, to indicate to the operator or attendant that the printing plate to which it belongs is not to be printed from, but is to be passed through the printing apparatus idly while maintaining its relative position in the list or series of plates, whereas, when the tab is shifted to another location, it will serve as an indicator by its mere

relative position that this particular plate is to be printed from when it is placed or arrives at the impression point on the printing apparatus, the operator controlling the printing of the plate or skipping it by any suitable means, or this being done automatically by selector mechanism. This shiftable tab therefore affords the means by which the bookkeeper can indicate whether or not the account of the party whose name appears on the plate has been settled. If shifted to one position, the tab indicates account paid. If shifted to the other position, it indicates that the account remains unpaid. In the former case no bill would be sent out and the plate therefore would be skipped in the printing, whereas in the latter case a bill would be sent and the plate would be printed.

In the particular form shown in Figs. 1 and 2 in which the main body of the tab is wider than those portions or tails 4 and 5 which extend through the terminal openings at *a*, *b*, and lie in the recesses of the rolled margin, the construction affords stop shoulders or edges 6 which limit the shifting movement of the tab and determine its different indicating positions. These shoulders come against the termini of the rolled margin at *a*—*b*, and afford a simple and certain way of determining the position of the tab, the widened central or main portion thus performing a plural function in that it provides space for receiving indicating marks or inscriptions of considerable size and extent, and also it provides the means for limiting the shifting movement of the tab and determining its positions, though it will be understood that I do not limit myself to this means of stopping or determining the different positions of the tab. For holding or restraining the tab against movement when set in either of its positions to which it may be adjusted, various means may be provided, but in the particular construction shown I utilize the means disclosed in the Letters Patent of Montague & Lee above noted, namely: by making the tail portion 4 or 5 or both of them of such form as to engage with considerable friction the walls of the recess in the rolled margin in which they lie. This means consists in bending the extensions or tail portions as at 19, Fig. 1^b, to make them have spring contact with the walls of the recess in the rolled margin.

In Figs. 1 and 2 I show also tabs 7, 8, at the corners of the printing plate, these being substantially of the same form as illustrated in the patent, above noted, and having a tail or extension piece entering a terminal portion of the rolled margin, as above described.

A tab such as at 3 may be used at either one or both edges of the plate. The ends 65 of the rolled margin at *a*—*b* are at right

angles to the edge of the plate, but I prefer to form these edges as shown at 9, Fig. 1, at an inclination to the edge of the plate, the advantage being that as the plates are moved one along the other, for instance 70 when being fed automatically, one by one, from a pile in the hopper of the machine, or when being discharged into a stacker chute, they will not interlock and therefore will not fail to feed, as otherwise might 75 be the case. These inclined edges may be beveled to accentuate the effect.

As shown in Fig. 3, the tab 3' is substantially like the tab 3 above described as to its general form and manner of attachment 80 to and adjustment on the printing plate, but it has the additional feature that it carries an adjustable indicator 10 consisting of a pivoted member which may be set in either its full line or dotted line position 85 to determine whether this plate is to be printed or skipped, this member thus serving as a selecting feature to coöperate with any suitable selecting mechanism on the machine, or this may be used as a visual 90 indicator to the operator at the printing machine to indicate to him whether he is to control the printing mechanism so as to print or skip this plate.

In this Fig. 3 also I illustrate the fact 95 that tab 3' may bear any suitable inscription as well as serving as a selective element in connection with the member 10. In this figure also I show a selective tab or element 11 pivotally mounted on the end of the 100 printing plate, which may be moved into any one of two or more positions. Openings are shown in the several figures at 12 to coöperate with suitable selecting devices to pass therethrough.

In Fig. 3 a series of tabs are shown marked Jan., Feb., Mar., April, to classify the plates by months. These tabs are shown in detail in Fig. 3^b, and their manner of attachment to the plate is shown at 110 3^a. They may be in the form of spring clips. The openings in the rolled edge for receiving these tabs are indicated at 13 in Fig. 3 and Fig. 3^c, and it will be noticed that the tabs here are introduced at right 115 angles to the axis of the rolled margin. The openings for receiving these tabs may be made as indicated at 13' with curved or inclined edges.

In Fig. 4 a tab 3'' is shown which may 120 have all the characteristics of the tabs 3 and 3' above described, and in addition it may be constructed to permit the use of a removable slip or card, as at 14, held by an overturned edge 15 of the tab, and by clips 125 16 pressed out from the body of the tab. As above indicated, this feature of a removable card may be carried out in connection with either of the tabs 3 or 3' above mentioned. The lower tab in Fig. 4 is 130

shown with notches for the purpose of indicating any particular month or classification as Feb., Aug.

In Fig. 5 I show a tab provided with a removable member bearing the information or indicating marks, this part being in the form of a metal clip 17 which may be sprung on or removed from the main part of the tab. A plurality of these removable clips 10 may be provided for a single tab, as shown in Fig. 5^a, to contain a plurality of items any one of which may be changed by removing it and replacing it with another to suit requirements.

15 It will be noticed that the tabs like 3, 3', while adjustable in relation to the plate to serve as indicators or as selecting means, maintain their connection with the plate, and that this connection is the same as that 20 disclosed in the patent above referred to in that the rolled marginal portion of the plate is provided with a terminal opening axially in line with the recess in the margin, the tab having a portion inserted in the terminal 25 opening and extending within the recess.

While I have referred to the margin as being "rolled" and that it is "cut away" at one point, it will be understood that these terms are used for convenience of description, as it will be understood that the margin may be formed otherwise than by rolling the metal upon itself and the space intermediate of the length of the margin or at the end thereof may be provided in a way other than by cutting out a portion of the margin. I do not limit myself to cutting away or omitting the whole of the rolled margin at any one point. For instance, only one 35 wall or part of one wall of the rolled margin may be omitted, in which case the terminal openings would be provided for receiving the tab ends as above described, and the intact wall or part wall will afford a backing for the tab.

40 The shiftable tab 3 may serve not only as a visual indicator, but as a selective tab to coöperate with selecting mechanism for performing or skipping the printing operations. For instance, when the tab is shifted into one 45 position contact of the selecting mechanism may be made therewith, whereas when the tab is shifted to another position it will miss contact with the selecting mechanism, in the one case performing printing and in the other case skipping the printing, or the reverse. This selecting may be accomplished in a manner similar to that disclosed in my application filed September 16, 1914, 50 #861,973, contact being made either with an extension on the tab or with the body 55 of the tab itself which may be provided with projections as in the application referred to.

I claim as my invention:

60 1. A printing plate having a rolled margin with a portion omitted, said rolled margin

65 having a recess within it, and a terminal opening axially in line with said recess, and a tab having a portion extending into the said recess to hold the tab in place, said tab bearing indicating means and being adjustable in the space left by the omitted part of the margin, the said indicating means being exposed in the different positions of the tab, substantially as described. 70

75 2. A printing plate having a rolled margin with a portion thereof omitted leaving a space intermediate of its length, said rolled margin having a recess within it with terminal openings axially in line with said recess, and a tab having a portion at each end extending through the adjacent terminal opening and into the recess in the rolled margin to hold the tab in place, said tab bearing indicating means and being adjustable in the space left by the omitted part of the margin, the said indicating means being exposed in the different positions of the tab, substantially as described. 80

85 3. In combination a printing plate having a rolled margin with a portion omitted or cut away intermediate of its length, a tab having a portion at each end extending into the rolled margin, said tab being adjustable lengthwise of the margin at said cut away 90 part and having stop means to determine the different positions of the tab, substantially as described. 95

100 4. In combination a printing plate having a rolled margin with a portion omitted or cut away intermediate of its length, a tab having a portion at each end extending into the rolled margin, said tab being adjustable lengthwise of the margin at said cut away part and having stop means to determine the different positions of the tab, said stop means 105 consisting of shoulders on the tab to strike against the ends of the rolled margin at the cut away portion, substantially as described.

110 5. In combination a printing plate having a rolled margin with a portion omitted or cut away intermediate of its length, and a tab having an extension at each end lying in the recesses of the rolled margin at each side of said cut away portion, the main part 115 of the tab extending laterally beyond the rolled margin of the plate, substantially as described.

120 6. In combination a printing plate having a rolled margin with a portion omitted or cut away intermediate of its length, and a tab having an extension at each end lying in the recesses of the rolled margin at each side of said cut away portion, the main part 125 of the tab extending laterally beyond the rolled margin of the plate, said tab being shiftable to occupy different positions in the space between the ends of the margin, substantially as described.

130 7. In combination a printing plate having a rolled margin with a portion thereof

omitted, a tab having a portion fitting in the recess within the rolled margin and adjustable to different positions in relation to the omitted portion of the rolled margin and 5 while maintaining its connection therewith, and a removable indicating member carried by the tab, substantially as described.

8. In combination a printing plate having a rolled margin with an opening in the edge 10 thereof communicating with the recess within said rolled margin, and a spring tab inserted in said opening, substantially as described.

9. In combination a printing plate having 15 a rolled margin, with a series of openings in the edge thereof communicating with the recess within said margin, and tabs fitted to said openings, substantially as described.

10. In combination a printing plate having 20 a rolled margin with an opening in the edge thereof communicating with the recess in the margin, and a spring tab consisting of a member bent upon itself and inserted in said opening, substantially as described.

25 11. In combination a printing plate having a rolled margin with a portion thereof omitted, a tab having a portion fitting in the recess within the rolled margin, and a removable indicating member carried by the 30 tab, substantially as described.

12. The combination with a printing plate having a rolled margin with an omitted portion and with a recess in said margin and a terminal opening leading to said recess at said omitted portion, a tab having a portion extending through the terminal opening into the recess, said tab being adjustable to different positions in the space left by the omission of margin while maintaining its connection with the rolled margin, said tab 40 having a portion to make or miss contact with selecting mechanism according to its position, substantially as described.

13. In combination with a printing plate having a rolled margin with a portion of 45 said margin omitted and with a recess in said margin and a terminal opening leading to said recess, a tab having a portion extending through the terminal opening into the recess and having its main portion extending laterally beyond the rolled margin, said tab being adjustable to set its main portion in different positions relative to the printing plate, substantially as described.

In testimony whereof, I affix my signature 50 in presence of two witnesses.

ROBERT GIBSON GRISWOLD.
